UNITED STATES PATENT OFFICE.

HENRY W. DEAN, OF BOSTON, MASSACHUSETTS.

LASTING-MACHINE.

SPECIFICATION forming part of Letters Patent No. 319,797, dated June 9, 1885.

Application filed March 9, 1885. (No model.)

To all whom it may concern:

Be it known that I, HENRY W. DEAN, of Boston, county of Suffolk, and State of Massachusetts, have invented an Improvement in 5 Lasting-Machines, of which the following description, in connection with the accompanying drawings, is a specification, like letters on the drawings representing like parts.

This invention has for its object to improve 10 the construction of lasting-machines.

In my improved machine the last containing the boot or shoe to be lasted is mounted at its heel upon a heel rest or pin, and at its toe upon a toe-rest, and the heel and toe clamping plates are then closed by hand upon and so as to embrace the upper at the heel and toe of the last. The main shaft is then started, and the heel and toe crimping jaws are moved bodily forward partly over the heel and the 20 toe of the last. The toe of the last is lifted. The side rubbers are then elevated to bring their upper edges up to the edge of the bottom of the last, thus straining the upper about the top of the last. The side jaws are moved forward 25 over the last, laying the edges of the upper thereon over on the inner sole on the last, and thereafter the heel and toe jaws are closed to complete the crimping of the upper at the heel and toe, and at the same time the heel of the last is elevated. In order to shorten the 30 stroke and better control the movement of the heel and toe crimping jaws, I have mounted the pivot of the jaws on a slide-plate, and have placed the usual roller or other studs at the rear ends of the jaws into diagonal slots made 35 in a jaw-closing slide-plate, rather than in a stationary plate, as heretofore, and I have provided independent means for moving both the said plates in the proper order of time. The 40 spring of the bottom of the last varies very considerably in different shops, and every style of shoe has its peculiar spring, and one of the most difficult things in lasting has been to readily adapt the side lasting-jaws to the 45 spring of the last and to lasts of different lengths or sizes. To obviate this difficulty, I have devised novel side lasting devices, composed of long fingers pivoted at their rear ends to permit them to be readily turned more 50 or less, and between their ends the said fin-

gers are supported in independent but vertically-adjustable guides or boxes, each guide or box having a projection to engage and cooperate with the guide or box next to it, so that as the said guides are adjusted vertically 55 the adjustment of one guide to a position higher or lower than the one next to it will more or less oscillate the adjacent guide, and consequently tip the finger held therein or thereon out of true horizontal line from edge 60 to edge, thus causing each of the said fingers to accommodate its under flat side to the spring of the last. These guides are independently adjustable, to thereby enable each finger to be placed in any desired vertical position, accord- 65 ing to the spring of the last. For longer or shorter lasts a greater or less number of fingers may be employed, the number employed being determined by the length of the last. The guides and the end bearings for the side 70 lasting devices or fingers are mounted upon horizontally-movable carriages.

The particular features in which my invention consists will be pointed out in the claims at the end of this specification. 75

Figure 1 is a top or plan view of my improved lasting-machine with the covering-plate for the toe-crimping jaw and its actuating parts removed. Fig. 2 is a side elevation of Fig. 1, the said covering-plate being in position. Fig. 3 is a horizontal vertical section of Fig. 1 in the dotted line $x\ x$. Fig. 4 is a vertical cross-section in the line $x'\ x'$, Fig. 2. Fig. 5 is a detail of the heel support or pin. Fig. 6 is a view of the reverse of the cam 85 shown in Fig. 4. Fig. 7 is a sectional detail showing the cross-head upon which are mounted the levers carrying the side rubbers; Fig. 8, a detail of the cam for operating the said cross-head. Fig. 9 is a detail side elevation 90 of the heel-jaw and its operating devices detached from the machine, the cover-plate for the said jaws being broken out. Fig. 10, in two views, shows one pair of crimping-jaws and the slide-bar upon which they are pivot- 95 ed. Fig. 11 shows the slotted jaw-closing slide-plate in detail. Fig. 12 is a detail of the end bearing for one of the side lasting-fingers. Fig. 13 is a top view thereof. Fig. 14 is a detail of one of the guides, boxes, or center sup- 100

ports for one of the fingers. Fig. 15 is a development in a plain surface of the cams for moving the crimping-jaws and the jaw-closing slide plate, and Fig. 16 is an elevation of one 5 of the guide holding and adjusting devices for the guides or boxes.

The frame-work A, of suitable shape to sustain the working parts, has suitable boxes to sustain the main rotating or cam shaft A', it 10 having splined upon it the cams A² A³—one to actuate the heel and the other the toe crimping devices, to be described—each cam having like cam-grooves 2 3, the shape of which is best shown in Fig. 15, the said grooves being, 15 however, made as rights and lefts. The cam-shaft A' has fast on it the cams A⁴ A⁵.

The frame-work A, at its top and along its sides, is provided with suitable guideways for the reception of the like carriages B B, which 20 are engaged at their under sides (see Fig. 4) by the upper ends of levers B' B', pivoted at B', and provided at their lower ends with roller or other studs, B³, that enter the diagonal slots B⁴ in the cross-head B⁵, it having a suitable roller or other stud, which enters a cam-groove, 5, (see Fig. 6,) in the cam A⁵, the reciprocation of the said cross-head causing the 25 said carriages to be reciprocated toward and from the center line of the last. Each carriage has suitable cross-pieces thereon, which receive the screws 6, having fast collars 7 thereon just below their heads, the space between the head of each screw and its collar 7 being used to receive the slotted foot of the 30 end bearing, a, the latter near its upper end having an opening for the reception of the tang 8 at the rear end of the side lasting-finger, C, the said tang being retained therein loosely by a suitable bolt or catch, a', actuated by a spring, 10, (see Fig. 12,) and preferably shielded by a shield, a², the rear end of each finger C so held being free to oscillate in the said end bearing, as may be desired. Each finger C is extended through a guide 35 or box, b, (shown in detail, Fig. 14,) and each guide has, at each side, a slotted ear, b'. These ears b' are extended into guide adjusting and holding devices b², (see Fig. 16,) made as loops held between the under side of the head of a screw, 12, and a collar, 13, thereon, the said screws entering and being made adjustable in a cross-beam of the carriage B. By turning the screw 12 the guide adjusting and holding device b² may be raised or lowered, 40 and, acting each one upon one of the ears b' of the guides b, the latter guides are tipped more or less, thereby turning the fingers C more or less out of true horizontal position in the direction of their width, causing the said fingers to occupy different positions one with relation to the other, thereby adapting each finger to the spring or curve of the last immediately at that point where the said finger is to pass over the edge of the last to lay the 45 upper at the sides and shank thereof, over

upon the bottom of the last or the inner sole thereon, to be then fastened in the usual way.

The toe-rest is composed of a block, d, (see Fig. 4,) pivoted upon a post, d', supported by a spring, 14, (see Fig. 3,) the said shank being 70 placed in a suitable guide, herein shown as a box, d², held loosely by the screws 15 in slots 16 therein, the said guide at its lower end having a roller, 17, which is acted upon by the cam A⁶ when the toe-rest is to be lifted, as described, which is done immediately after the toe-crimping jaws are moved forward, the said cam A⁶ being fast to the cam-cylinder A³. The heel support or pin e is pivoted upon a small block, e', held loosely in a shank, e², guided 75 at its lower end in a guide, e³, the said shank being provided with an elongated central opening, 18, to receive the main shaft A'. The shank e² has a laterally-projecting roller-stud, 19, that enters a cam-groove, 20, (see Figs. 3 80 and 4,) in one face of the cam A⁵, the said cam-groove being of such shape as to lift the heel support or pin and the heel of the last after the heel-crimping jaws have been moved forward and while they are being closed, such 85 lifting of the heel-pin to thus break down and better set the leather and counter at the heel end of the shoe. At its end the frame-work has suitable guideways for the reception of the heel and toe carriages E F, provided with depending legs that receive between them, respectively, the cam hubs or cylinders A² A³, projections from each end of the said hubs entering the said legs, one of the said projections having fast on it the cam A⁶. The top 90 plates of the carriage E F, both alike, have suitable guideways to receive one of the slide-plates e, having pivoted upon them at e' the crimping-jaws e², each jaw having a roller or other stud, 22, (see Fig. 10,) that enters a 95 slot, 28, in a jaw-closing slide-plate, f, (see Figs. 1 and 11,) also fitted to slide longitudinally in guideways of the said carriage. The slide-plate e has a lug, 23, that is engaged by the upper end of a lever, 24, of the first 100 order, the said lever at its lower end having a roller or other stud or pin that engages a slide-block, 25, (see Fig. 9,) held between suitable guide-ledges, 27, of the said carriage, the block 25 having a roller or other stud, 26, 105 that enters the cam-groove 2 of one of the cam-hubs A² or A³. The lever 24 moves the slide-plate e only longitudinally. The jaw-closing slide-plate f is connected, as herein shown, by a bail or link, 29, with the upper end of a lever, 30, of the first order, it at its lower end engaging a slide-block, 31, held and guided by the ledges 27, the said slide-block having a roller or other stud, 32, to enter one of the cam-grooves 3 of one of the cam-hubs A² or A³. 110 The cam-grooves 2 and 3 are parallel for part of their length, and while the studs 26 and 32 are in the parallel parts of the said grooves the slide-plate e is moved forward, and at such time it will be understood that the crimping- 115

jaws e^2 carried by the said plates are not closed; but at the proper time during the further rotation of the said cam-hubs $A^2 A^3$ the cam-groove 3, acting on the stud 32, moves the block 31, lever 30, and plate f forward, causing the cam-slots 28, by their action on the stud 22, to close the crimping-jaws at the toe and heel of the shoe, the said jaws during their closing movement, as described, about their pivots e' not necessarily being moved forward. The heel and toe crimping jaws are both alike, so the same letters have been used to designate like parts, and the description of one of them will suffice for both. The heel and toe carriages, provided, respectively, with threaded nuts $E' F'$, receive in the said nuts a shaft, G , provided with right and left threads, the rotation of the said shaft enabling the toe and heel carriages to be adjusted toward and from each other, according to the length of the boot or shoe to be lasted. The toe and heel carriages each have a spring-plate, g , of usual shape, to come in contact with the upper at the toe and heel of the last. The side rubbers are composed of levers $H H'$, pivoted at 33 on a vertically-movable cross head, H' , the upper ends of the said levers having connected to them by the screws 34 the shanks h of spring-arms H^2 , the upper ends of which, curved to conform substantially to the outlines of the inner and outer sides of the last, are faced with india-rubber or leather, as at h' , the said material being connected with the said spring-arms by suitable pins, 35. These side rubbers having the spring-arms, as described, are free to adapt themselves to the thickness of the last and the upper thereon, and are caused to act upon and are moved vertically while in contact with the upper, to thus stretch the upper about the last preparatory to moving the side lasting-fingers, C , over the last. The cross-head H' is provided with a roller or other stud, 36, which enters a cam-groove, 37, in the cam A^4 , fast on the shaft A' . The lower ends of the levers H are acted upon by springs H^4 , that normally act to cause the rubbers to hug the last or the boot or shoe thereon, and the said levers H are also connected by a cord or chain, m , joined with a foot or other lever, m' , the free end of which enters a suitable guide having teeth or notches, (see Fig. 2,) as usual, by which to hold the said lever in place.

When the last is to be put on the heel pin or support, or is to be removed therefrom, the operator will depress the treadle m' .

Fig. 2 clearly shows the fingers adjusted into position to accommodate them to the spring of the last.

The guides b and the guide adjusting and holding devices b^2 constitute a flexible or jointed support for the side lasting devices or fingers, C , at a point back from their working ends, the said guides and adjusting devices resembling a chain, and, if desired, the guides

and guide adjusting and holding devices may be jointed together like the links of a chain; or the guides b might be mounted on an india-rubber strip or on an ordinary flat chain.

By connecting the guides b together, as described, but one screw in number more than the number of fingers used need be employed to adjust all the fingers; but if the said guides were not loosely connected each with the other, at least two screws would be needed to adjust each guide, and the use of these extra screws would not permit the close arrangement of the fingers.

I do not broadly claim adjustable side lasting-fingers.

I claim—

1. In a lasting-machine, the series of guides b and the guide adjusting and holding devices b^2 , loosely connecting the guides together, and the bearings a , and the horizontally-arranged fingers C , placed in the said guides, combined with screws to adjust the guides vertically and hold them in place, and with a side lasting-carriage to move the said fingers and their supports, to operate as described.

2. In a lasting-machine, the side lasting-carriages, the end bearings, a , mounted thereon, and the side lasting devices or fingers pivoted at their outer ends in the said bearings, combined with a series of loosely-connected vertically-adjustable guides, b , to receive and hold the said fingers, substantially as described.

3. In a lasting-machine, the side lasting-carriages, end bearings, a , mounted thereon, and the side lasting devices or fingers pivoted at their outer ends in the said bearings, combined with a series of connected guides, and with means, substantially as described, to adjust both the said bearings and the said guides, substantially as described.

4. In a lasting-machine, guide adjusting and holding devices, the series of loops, and the screws to hold and adjust them, combined with the intermediate guides, b , having ears to enter or be engaged by the said guide adjusting or holding devices, substantially as described.

5. In a lasting-machine, the side lasting devices or fingers provided at their rear end with tangs, and bearings a , to receive the said tangs, combined with catches to engage the said tangs and loosely support and hold the said fingers, and with a series of loosely-connected vertically adjustable guides, b , for the said fingers, between the said bearings and the inner end of the fingers, substantially as described.

6. In a lasting-machine having toe and heel carriages, a slide-plate, e , and crimping-jaws pivoted thereon, combined with the independently-reciprocating slotted jaw-closing slide-plate f , adapted to engage and close the said jaws, substantially as described.

7. In a lasting machine, the supports for the heel and toe of the last, and the side rubbers, $H h h'$, combined with the cross-head,

and with means, substantially as described, to operate the said cross-head.

8. The supports for the heel and toe of the last, and the side rubbers, $H\ h\ h'$, combined with the connected treadle to separate or move the said side rubbers away from each other, substantially as and for the purpose described.

In testimony whereof I have signed my name to this specification in the presence of 10 two subscribing witnesses.

HENRY W. DEAN.
